HEEL BREASTING MACHINE

Erastus E. Winkley, Lynn, Mass., assignor to
 United Shoe Machinery Corporation, Flemington, N. J., a corporation of New Jersey

Application May 11, 1944, Serial No. 535,023

28 Claims. (Cl. 12—47)

This invention relates to shoe machinery and is illustrated as embodied in a heel breasting machine.

In the manufacture of shoes having built-up leather heels, for example, it is common practice after the heel has been attached to the shoe to breast said heel by the use of a reciprocable knife movable heightwise of the heel into engagement with the outsole of the shoe. In breasting the heel, it is desirable that the entire heel breast shall be trimmed clean. It is also important that movement of the breasting knife shall cease upon engagement with the outsole, since it will be apparent that cutting into the outsole not only mars the appearance of the shoe, but weakens the outsole.

Various constructions have been proposed with a view to insuring that the heel breasting knife during its breasting movement shall cut to, but not into, the outsole. Such prior constructions comprise a gage or position testing member which engages the shank portion of the outsole of the shoe and which is utilized to set an abutment the position of which governs the extent of movement of the knife toward the outsole. The gages of such prior constructions engage portions of the outsole of the shoe which are somewhat remote from the line of engagement of the heel breasting knife with the outsole. Since the shank angle of the outsole varies to a considerable extent in accordance with the size and/or style of the shoe, it will be apparent that with such an arrangement it is difficult to control the movement of the knife so that such knife cuts to, but not into, the outsole during its heel breasting operation.

The forward ends of attaching faces of built-up leather heels are usually provided with beveled surfaces which are commonly known as "Coburn lips" and are disclosed in United States Letters Patent No. 364,217, granted June 7, 1887, on an application filed in the name of G. R. Coburn. In such a construction, the above-mentioned beveled surface of the unbreasted built-up heel attached to the shoe is spaced slightly, but not perceptibly, from the opposed shank portion of the outsole of the shoe, thus forming a slightly open crease. During the heel breasting operation the breast portion of the heel is usually trimmed back to approximately the rear end of the beveled surface which, as stated in said patent, is provided in order to insure against the rear end of the shank of the outsole of the finished shoe being marked by the unbreasted heel during the heel attaching operation.

It is an object of the present invention to provide an improved heel breasting machine of the general type above referred to, having none of the above mentioned drawbacks. With the above object in view and in accordance with a feature of the present invention, the illustrative heel breasting machine comprises means for supporting a shoe, a gage shaped and arranged to occupy a crease, such as that above referred to, formed between an outsole of the shoe and the forward end of the attaching face of an unbreasted heel attached to the shoe, a heel breasting knife, and means operatively associated with the gage for varying the cutting stroke of the knife in accordance with the position of the gage.

In the illustrative machine the shoe is supported upon a jack and is clamped in the usual manner to the jack by means of a presser plate which operates against the pre-finished top-lift 20 of the heel of the shoe, the machine being of the general type disclosed in United States Letters Patent No. 1,080,376, granted December 2, 1913, on an application filed in the name of Ralph C. Simmons. The above-mentioned gage for 25 testing the position of the work has the general shape of a sickle, a tip of the gage which occupies said crease being beveled and corresponding to the tip of the sickle. The gage has a cylindrical shank, corresponding to the handle of 30 the sickle, pivotally mounted in a vertically movable gage carrying slide. Threaded into the top of the gage slide is an abutment constructed and arranged to be engaged, during downward breasting movement of the knife, by a trip lever carried 35 by a slide to which the knife is secured. Upon the engagement of the trip lever with the abutment, the knife slide is disconnected from an operating slide, which is power driven through a one-revolution clutch, thereby causing downward 40 movement of the breasting knife toward the outsole to cease.

The gage, which is free to tilt approximately 45 30° upon the gage slide, has a curved arm which extends forward from the cylindrical shank and is arranged at one side of the axis of said shank, the construction being such that the gage is unbalanced and when not in engagement with the work assumes a horizontal position determined by a stop on the gage slide. When the jack upon 50 which the shoe is mounted has been swung to an upright position, the gage slide is lowered, causing the curved arm of the gage to engage the shank portion of the outsole of the shoe, the gage pivoting about the axis of its shank until 55 the tip of the gage has been swung into en-

gagement with the slightly inclined shank portion of the outsole of the shoe.

The shoe is then swung, together with the jack, until the tip of the gage occupies the crease formed between the shank portion of the outsole of the shoe and the forward end of the attaching face of the heel. The shoe is positioned lengthwise in the machine in the usual manner during the clamping of the shoe in the machine with the breast edge of the prefinished top-lift of its heel in alinement with the forward edge of the presser plate. When the shoe has been positioned in the machine, a treadle is depressed, causing the presser plate to be lowered with yielding pressure against the top-lift of the heel, as above described. Continued depression of the treadle causes a one-revolution clutch to be tripped, with the result that the knife moves downward, past the forward edge of the presser plate and the breast edge of the prefinished top-lift, to breast the heel. The tip of the gage is arranged just to one side of the path of movement of the cutting edge of the knife, the trip lever actuating abutment being so positioned by the tip of the gage that downward movement of the knife ceases when its cutting edge has moved to the gage, thereby insuring that the knife shall cut downward to, but not into, the outsole during its breasting stroke.

In order to insure against the tip of the gage being hammered against the shank portion of the outsole of the shoe when the trip lever engages said abutment and thus marring the appearance of said outsole, the gage carrying slide, after the shoe has been positioned in the machine and the position of its outsole tested as above explained, is backed up rigidly against the action of the trip lever by a cam-operated member which is automatically moved to its backing-up position before the tripping of the clutch.

Preparatory to removing the shoe mounted upon the jack from the machine after the breasting of the heel, the gage is automatically moved to an inoperative position away from the shoe. The gage is lowered by gravity back to its operative position into engagement with the shank portion of the outsole of the next shoe to be breasted, the gage being released for movement to its lowered operative position in response to movement of the jack back to its vertical operating position.

The various features of the invention will be understood, and appreciated from the following detailed description read in connection with the accompanying drawings, in which

Fig. 1 is a perspective view, partly broken away, of the illustrative machine;

Figs. 2 and 3 are front and end views, respectively, partly broken away and partly in section, of the machine;

Fig. 3a is a section on line IIIa—IIIa of Fig. 5;

Fig. 4 is a view similar to a portion of Fig. 3, but showing the work position testing gage in its raised inoperative position;

Figs. 5 and 6 are sections on lines V—V and VI—VI, respectively, of Fig. 2;

Fig. 7 is a plan view of mechanism for facilitating the positioning of work in the machine;

Fig. 8 is a perspective view of an unattached built-up leather heel having a Coburn lip; and

Figs. 9 and 10 are perspective and side views, respectively, showing the heel, after it has been attached to the shoe, in the process of being breasted.

The illustrative machine is described with reference to breasting a built-up leather heel 20

attached to a shoe 22 mounted upon a last 24 (Figs. 3 and 4) and comprises a work support or jack 26 (Figs. 1 and 3) upon which the shoe arranged bottom up is mounted, a clamping or presser plate 28 which is lowered into engagement with the tread end or top-lift 30 of the heel, and a knife 32 which is moved downward a variable distance past a laterally incurved forward edge 34 (Fig. 9) of the presser plate 28 to breast the heel. The machine is of the general type disclosed in said Letters Patent No. 1,080,376, the clutch of the machine being practically identical with the clutch of the machine disclosed in United States Letters Patent No. 1,597,210, granted August 24, 1926, on an application filed in the name of Ralph C. Simmons.

As above explained, the unbreasted built-up leather heel 20 (Fig. 8) has at the forward end of its attaching face a beveled surface or "lip" 36 which is provided in order to insure that the shank portion 38 (Figs. 9 and 10) of the outsole of the finished shoe, which portion before the heel breasting operation underlies the lip, shall not be marked by said heel during the heel attaching operation. The lip 36 may be considered part of the cut or attaching face 40 (Fig. 8) of the unbreasted heel 20. It will be apparent (Fig. 10) that after the unbreasted heel has been attached to the shoe there is formed between the shank portion 38 of the outsole of the shoe and the beveled surface 36 of the unbreasted heel a slightly open crease 42 (Fig. 10), which is hardly perceptible but the width of which has been exaggerated slightly for purposes of illustration. As will be explained later, the crease 42 is utilized to receive a gage or position testing member 44 forming part of mechanism for varying the downward extent of the breasting stroke of the knife 32, the arrangement being such that a cutting edge 45 of the knife during its breasting stroke moves downward into engagement with, but not into, the outsole of the shoe. The gage 44, which has a tapered end or tip constructed and arranged to occupy the central portion of the crease 42, is of arcuate shape as viewed from above (Figs. 7 and 9) and is provided with a cylindrical shank 46 fitting for pivotal movement in a horizontal bore 48 of a bushing 49 secured to a slide 50 vertically movable in guideways 52 of the machine frame 53. Welded to the shank 46 of the gage 44 at one side of the slide 50 is a collar 54, and mounted upon said shank at the other side of the slide is a washer 56 which nonbindingly engages the bushing 49 and is held in position by a nut 58 threaded onto said shank.

In order to limit the degree of tilting movement of the gage 44 about the axis 60 of its shank 46, the collar 54 is provided with a notch 62 (Figs. 2, 9 and 10) in which registers a pin 64 secured to the slide 50, the arrangement being such that the gage is arranged approximately horizontal when the machine is idle, the gage being held by gravity in such position with a shoulder 65 (Figs. 9 and 10) of the collar 54 in engagement with the pin 64. When, as will appear later, the gage 44 is lowered against the shank portion of the outsole of the shoe 22, the tip of the gage, which tip is in approximate alinement with the axis 60, will tilt slightly with relation to the slide 50 about the axis in accordance with the angle of inclination of the shank portion of the outsole of the shoe with which it is in contact, thereby facilitating the entry of the tip of the gage 44 into the crease 42.

The gage 44 may be described as sickle-shaped,

the cylindrical shank 46 of the gage corresponding to the handle of the sickle. A gage arm 67 extending forward from the shank 46 is curved lengthwise of the shoe, as best shown in Figs. 7 and 9, and is arranged at one side of the axis 60, the center of gravity of the gage being offset from said axis so that when the machine is idle the arm will be swung to its approximate horizontal position above referred to.

Threaded into the gage slide 50 is a stop or abutment 66 which, as will appear later, during downward movement of a knife carrying slide 68, hereinafter referred to as the knife slide, in vertical guideways 70 (Figs. 2, 6 and 7) is engaged by a horizontal arm 72 (Figs. 1, 2 and 3) of a bell-crank, trip or trip-off lever 74 fulcrumed on a pin 76 (Figs. 2 and 3), which is mounted upon the knife slide, in order to disconnect the knife slide from an operating slide 78 (Figs. 3 and 6), thereby limiting downward movement of the knife slide. The stop 66, together with the gage slide 50, may be referred to as an abutment.

The breasting knife 32 is clamped against a bar 80 (Fig. 2) of the knife slide 68 by two setscrews 82 (Figs. 2 and 3) threaded into another bar 84 of the slide. The operating slide 78 is movable in vertical guideways 86 (Figs. 6 and 7), which are continuations of the guideways 70, and has pivoted to it at its lower end a connecting rod 88 (Figs. 1 and 3) the lower end of which is pivoted to a crank 90 (Fig. 1) on a drive shaft 92.

The jack 26 comprises an upstanding post 94 having a lower threaded end 96 (Figs. 1 and 3) keyed against rotation in a cylindrical recess of a column 98. Mounted on the column 98 and threaded onto the lower end of the post 94 is a hand wheel 100 which may be rotated for initially raising or lowering the post. The column 98 is supported upon a bearing 102 (Fig. 1) mounted in the machine frame 53, swinging movement of the column from a substantially vertical operative position to a forwardly inclined loading position being limited by a shoulder 104 formed on the base of the machine frame. Pivoted to the upper end of the post 94 is a last supporting block 106 (Figs. 1 and 2) which may be swung into different angular positions in a vertical plane by turning a screw 108 (Fig. 1) which is threaded into the post and is engaged by the bottom of the block. The block 106 is provided with a transversely curved dovetail guideway 110 (Figs. 1, 3 and 4) in which fits a slide 112 carrying a last pin 114. Secured to and projecting upwardly and laterally from the post 94 is an arm 116 (Fig. 1) to which is adjustably secured a rest 118 for supporting the toe end of the shoe.

The presser plate 28 has secured to it a guide 120 (Fig. 2) which fits in a guideway 122 in the bottom face of a bracket 124, said plate being set in different adjusted positions lengthwise of said guideway by a wing screw 126 (Figs. 1 and 2) which is threaded into the bracket and passes through an elongated slot 128 (Fig. 2) in the plate. The bracket 124 is pivoted upon a fulcrum pin 130 carried by a slide 132 (Figs. 1 and 2) which is vertically movable in a guideway 134 (Fig. 2) formed in the machine frame 53 and has a forwardly projecting arm 136 operatively connected through a toggle 138 to one end of a lever 140 pivoted upon a bearing pin 142 secured to a boss of the machine frame.

The presser plate 28 is normally arranged in a horizontal position, a shoulder of the bracket 124 being held in engagement with a stop screw

144 (Figs. 1 and 2), adjustably secured to the slide 132, by a spring 146 the forward end of which is attached to a stud on the bracket and the rear end of which is attached to a stud on the slide.

Pivoted to the lever 140 is a two-part block 148 having a vertical bore through which passes a rod 150 operatively connected at its lower end to a clutch tripping treadle 152 (Fig. 1). Threaded onto the rod 150 is a nut 154 (Figs. 2 and 3) which, when the treadle 152 is released, is forced by a strong spring 156 (Fig. 1) against the bottom of the block 148 to move the lever to a raised idle position. Mounted upon the rod 150 and interposed between the block 148 and a wing nut 158 (Figs. 1 and 2) threaded onto the upper end of the rod is a spring 160, the arrangement being such that as the rod is lowered, when the treadle 152 is first depressed, the presser plate 28 is forced with yielding pressure against the prefinished top-lift 30 of the heel of the shoe mounted upon the jack 26.

The shoe is positioned lengthwise in the machine by swinging the column 98 about the bearing 102 as the presser plate 28 is lowered, the breast edge 162 (Fig. 9) of the prefinished top-lift 30 of the heel being alined with the concave forward edge 34 of the presser plate 28. The construction and arrangement of the machine is such that the trimming knife 32, the cutting edge 45 of which is concave lengthwise as well as heightwise of the shoe, during its downward movement just clears the concave forward edge 34 of the presser plate 28 and the breast edge 162 of the prefinished top-lift and continues downward to trim off the portion of the heel extending forward of the path of travel of the knife, as illustrated in Figs. 9 and 10.

The knife slide 68 is moved to its raised starting position, shown in Fig. 3, by the operating slide 78, which, during its upward movement, engages an overhanging flange 166 which is secured by screws 168 to the upper end of the knife slide and comprises a leather facing 170. Mounted upon a pin 172 carried by the operating slide 78 is a block 174 an inner face of which engages a face 176 of the operating slide 78 to insure that the block shall remain fixed to the slide.

In order that the knife slide 68 shall move downward in response to downward movement of the operating slide 78, there is provided the above-mentioned bell-crank lever 74, which is normally urged in a counterclockwise direction, as viewed in Fig. 3, against a face 178 of the knife slide by a leaf spring 180. When the machine is idle and during downward movement of the knife slide 68, a vertical arm of the bell-crank lever 74 is in engagement with a flat lower surface 182 of the block 174 which, as above stated, is carried by the operating slide 78. Downward movement of the knife slide 68, which is actuated through the bell-crank lever 74 by the operating slide 78, ceases when said lever has been moved from beneath the block 174 by the abutment 66 of the previously set gage slide 50.

The abutment 66 is initially set in different heightwise positions, through mechanism which has been partially described above and another mechanism which will appear later, to cause downward movement of the knife 32 to cease when its cutting edge 45 has moved into engagement with the shank portion 38 of the outsole of the shoe. The position of the shoe is tested by

causing the tip of the gage 44 to engage, as best shown in Fig. 10, the shank portion 38 of the outsole of the shoe underlying the beveled surface 36 (Fig. 8) of the unbreasted heel, the gage being so arranged that during the heel breasting operation the knife travels downward to the outsole and just misses the tip of the gage.

The guideways 52 (Figs. 2, 6 and 7) for the gage slide 50 is formed partly by a U-shaped frame 184 horizontal portions 186 of which fit in rabbeted portions of vertical retaining plates 188 secured by screws 190 to the machine frame 53. Secured by screws and dowels 192 (Fig. 2) to the horizontal portions 186 of the U-shaped frame 184 are vertical slide retaining plates 194 which overlap the front face of the gage slide 50. The U-shaped frame is initially set in a fixed position in the rabbeted portions of the retaining plates 188 by a cap screw 196 (Figs. 2 and 6) which is threaded into the right retaining plate 188 and has surrounding it a spring 198 opposite ends of which occupy recesses formed in the U-shaped frame 184 and the plate, respectively. By adjusting the U-shaped frame 184 as above described, it will be apparent that the tip of the gage 44 may be brought to its proper operative position beneath the cutting edge 45 of the knife 32, the arrangement being such that the central part of the cutting edge of the knife at the lower end of its movement just misses the tip of the gage.

The lower portion of the gage slide 50 is provided with a vertical slot 200, best shown in Figs. 1 and 2. Mounted upon a fulcrum pin 202 (Figs. 1, 2, 3 and 4) secured in bosses 203 (Figs. 1, 2 and 6) of the gage slide 50 is a pawl 204 having at its upper end a hook-shaped head 206 (Figs. 3 and 4). When the pawl 204 is in its operative position shown in Fig. 3, the head 206 of the pawl 204 is held against a beveled surface 205 on the slide 50 by a spring 207 opposite ends of which occupy recesses in the pawl and the gage slide, respectively.

Secured by screws 208 (Figs. 2, 3 and 6) to the knife slide 68 is a bar 210 the left end of which, as viewed in Fig. 2, extends downward and then rearward, a coil spring 212 (Figs. 1 and 2) being operatively connected through a threaded eye bolt 214 to the bar 210 and being secured at its upper end to the machine frame 53. Upon downward movement of the knife slide 68 the spring 212 is elongated, the arrangement being such that when the knife slide 68 is disconnected, as above described, from the operating slide 78, the spring serves to counterbalance somewhat the knife carrying mechanism and to start the knife slide upward before it is moved to its raised starting position by the operating slide.

The bar 210 has at its central upper portion a beveled surface 216 (Figs. 2, 3 and 4) and at its central lower portion a beveled surface 218. As the knife 32 travels downward to breast the heel, the gage slide 50 at such time being in its lowered operative position shown in Figs. 2 and 3, the beveled surface 218 of the bar 210 on the knife slide 68 engages the head 206 of the pawl 204 and swings the pawl about the fulcrum pin 202 in a counterclockwise direction, as viewed in Fig. 3, against the action of the spring 207. When the bar 210 has been moved below the head 206 of the pawl 204, the pawl moves back to a position in which its head overlies the bar. After the completion of the heel breasting operation, the bar 210 of the knife slide 68, upon upward movement of the slide, engages a shoulder

219 (Fig. 3) of the head 206 of the pawl 204 and thus moves the gage slide 50, together with the gage 44, to its raised position, shown in Fig. 4. When the gage 44 has been raised out of the way, the operator swings the jack 26, together with the shoe which has been operated upon, clockwise (Fig. 1) about the bearing pin 102 to its loading position in which the shoe is removed from the jack.

10 It is desirable to retain the gage 44 in its raised idle position, shown in Fig. 4, until the jack 26, upon which another shoe has been mounted, has been swung counterclockwise (Fig. 1) back to approximately its vertical position. In order to 15 cause the pawl 204 automatically to release the gage slide 50 from the knife slide 68 as the column 98 reaches a vertical position, the following mechanism is provided. The column 98 has secured to it by cap screws 220 (Fig. 1) a bracket 20 222 (Figs. 1, 2, 3, 4 and 6) to which is riveted a block 224 upon the flat upper face of which rests a carrier plate 226 through an elongated horizontal slot 228 (Figs. 1, 2 and 6) of which passes a screw 230 threaded into the bracket, the carrier 25 plate being rigidly secured to the bracket by the screw. Pivoted upon a shoulder screw 232 (Figs. 2 and 6) secured to the carrier plate 226 is a trip latch 234 (Figs. 2, 3, 4 and 6) which is normally held against a stop pin 236 (Figs. 2 and 6) secured to the plate by a spring 238 one end of which is fixed to the lower end of the latch and the other end of which is fixed to the carrier plate.

30 After the shoe has been placed upon the jack 26 in its loading position, the gage slide 50 then being in its raised position shown in Fig. 4, the jack is swung back, that is, in a counterclockwise direction as viewed in Fig. 1, about the fulcrum bearing 102, causing a beveled face 240 (Figs. 3 and 6) of a pin 242 secured to the latch 234 to engage a beveled surface 244 (Figs. 3, 4 and 6) at the lower end of the pawl 204, with the result that the pawl is swung in a counterclockwise direction, as viewed in Fig. 4, about its fulcrum pin 202 away from the bar 210, which, as above stated, is secured to the knife slide 68, thus enabling the gage slide 50 to drop. Downward movement of the gage slide 50 is limited by engagement of the gage 44 with the shank portion of the outsole of the shoe mounted upon the jack.

35 It will be noted (Fig. 10) that the gage 44 is arranged approximately horizontal and that the 40 arm 67 of the gage upon engaging the shank portion of the outsole of the shoe will pivot about axis 60 of its shank 46 until the tip of the gage has been swung into engagement with said shank portion. With the gage 44 thus positioned, the jack 26 is moved slightly to the right (Fig. 1) so as to align the breast edge 162 (Fig. 9) of the prefinished top-lift 39 of the heel with the forward edge 34 of the presser plate 28 and to cause the tip of the gage 44 to occupy the crease 42 formed between the shank portion 38 of the outsole of the shoe and the beveled surface 36 of the unbreasted heel.

45 In order to facilitate tilting the shoe to its proper lateral position on the jack 26 so as effectively to receive the action of the knife 32, the 50 illustrative machine may be provided with centralizing fingers 248 which are constructed and arranged to be engaged by the forward upper portions of the sides of the heel of the shoe. The 55 fingers 248 are geared together for equal and

opposite movement about fulcrum pins 250 (Figs. 2 and 7) carried by a forward extension of a plate 252 which is secured for heightwise adjustment through screw-and-slot connections 254 (Fig. 2) to the horizontal portions 186 of the U-shaped frame 184. The fingers 248 are constantly urged together by a spring 256 opposite ends of which are secured to studs 258 on the respective fingers. Movement of the fingers 248 toward each other is limited by engagement of a screw 260 carried by one of the fingers with a depending abutment 262 (Figs. 1 and 7) carried by the other finger.

As the jack 26 is swung to the right (Fig. 1) to remove the work from the machine, the trip latch 234 (Figs. 2, 3, 4 and 6), upon engagement with the lower end of the pawl 264, is swung in a counterclockwise direction, as viewed in Fig. 2, about the shoulder screw 232 so as to pass the pawl. The latch 234 will then swing back to its vertical position against the stop 236 so that it will trip the pawl 264, as above described, when the jack 26 is moved back to its vertical operative position.

It will be appreciated that the impact of the arm 72 of the bell-crank lever 74 against the abutment 66 should not be transmitted through the gage 44 against the shank portion of the outsole of the shoe, since such an impact would cause the outsole to be marked. Accordingly, the gage slide 50, after being set in its gaging position as above described, is rigidly backed up at its lower end by a cam follower 264 (Figs. 2, 3 and 5), which, as will appear later, is raised into engagement with the lower end of the slide.

Mounted upon the machine frame 53 are a pair of bearing plates 266, 268, best shown in Fig. 5, having opposed recesses forming an opening 270. The bearing plates 266, 268 are secured to the machine frame 53 through a yoke 272, best shown in Fig. 3a, which engages the rear faces of flanges 274 (Fig. 5) of the machine frame 53 and into which are threaded cap screws 276 (Figs. 2 and 5) passing through registering bores in the plates, the screws serving to clamp the yoke 272 and the bearing plates 266, 268 securely to the machine frame. Journaled in alined bushings of the bearing plates 266, 268 is a shaft 278 (Figs. 3, 3a and 5) extending rearwardly through a U-shaped recess of the yoke 272 and having pinned to its rear end a cam pulley 280 provided with a hub portion 282.

Arranged in the opening 270 (Fig. 5) between the bearing plates 266, 268 and secured to the shaft 278 is a cam 284 (Figs. 2, 3 and 5) engaged by the above-mentioned cam follower 264 which is secured to an arm 286 pivoted upon an enlarged cylindrical portion of a shoulder screw 287 (Figs. 2 and 5) threaded into the bearing plate 266. Occupying a circumferential groove 288 (Figs. 3, 3a and 5) in the hub portion 282 of the cam pulley 280 is a coil spring 290 one end of which is secured to the pulley by a screw 292 (Fig. 3a) and the other end of which is secured to the lower end of a depending rod 294 (Figs. 2, 3 and 3a) threaded into the yoke 272, the spring 290, through mechanism hereinafter described, being elongated or tensioned when the jack 26 is moved to its loading position.

When the spring 290 has been tensioned, the cam pulley 280 is in its position shown in Figs. 3, 3a and 5, a lock pin 296 secured to the cam pulley being in engagement with an upstanding lever 298 which is fulcrumed on a cylindrical portion of a shoulder screw 300 threaded into

5 a block 302 secured by screws 304 to the machine frame 53. The lever 298 is constantly urged toward the cam pulley 280 by a spring 305 (Figs. 3 and 5) the upper end of which is connected to the main frame 53 and the lower end of which is connected to the longer of two plates 306 mounted on the shoulder screw 300 and pinned to the lever.

10 As will appear later, the treadle rod 150 of the machine passes between the plates 306 and has secured to it a collar 308 arranged just above the upper edges of the plates the construction and arrangement being such that during the first part of the downward movement of the treadle rod the lever 298 is moved away from the lock pin 296, thus enabling the coil spring 290 to rotate the cam pulley 280, and therefore the cam 284, in a counterclockwise direction, as viewed in Figs. 2 and 3a, until the cam follower 264 has moved into engagement with the lower face of the gage slide 50. In order to limit movement of the cam 284 in said counterclockwise direction in accordance with the maximum throw of the cam, the bearing plate 266 has secured to it a stop 310 (Figs. 2, 3 and 5) which is engaged by a pin 312 carried by the cam.

30 Loosely mounted upon the forward portion of the shaft 278 is a pulley 314 (Figs. 2, 3 and 5) in a groove 316 (Figs. 3 and 5) of which registers one turn of a cable 318, said cable passing over loose pulleys 320, 322, best shown in Figs. 2 and 5, mounted for rotation upon shoulder screws 324, 327, respectively, and having its right end secured by a screw 326 to a lug 323 (Figs. 1, 2 and 5) adjustably secured to the bracket 222. In order to retain the cable 318 in timed relation with the pulley 314, the cable is secured in the groove 316 of the pulley by a screw 327. The left end of the cable 318 is secured to the upper end of a tensioning spring 329 (Figs. 1 and 2) the lower end of which is secured to a rod 330 threaded into the underside of the bearing plate 266.

45 When the shoe has been positioned in the machine with the crease 42 (Fig. 10), which is formed between the beveled surface 36 of the unbreasted heel and the shank portion 38 of the outsole of the shoe, occupied by the tip of the gage 44, the operator depresses the treadle 152. During the first part of the downward movement of the treadle rod 150 the presser plate 28 is lowered with clamping pressure against the prefinished top-lift 30, the jack 26 during the lowering of the presser plate being swung slightly lengthwise of the shoe to insure that the breast face 162 of the prefinished top-lift shall be in alinement with the forward edge 34 of the presser plate. Further downward movement of the treadle rod 150 causes the collar 308 (Figs. 3 and 5) on the rod to swing the lever 298 in a clockwise direction, as viewed in Fig. 3, about the shoulder screw 300, with the result that the cocked cam pulley 280 is released and rotates under the action of the coil spring 290 in a counterclockwise direction, as viewed in Figs. 2 and 3a, until the cam 284 has moved the cam follower 264 into engagement with the lower end of the gage slide 50. The cam follower 264 is retained against the slide by the spring 290 operating through the above-described mechanism. The slope of the cam 284 is such that upon engagement of the abutment 66 by the bell-crank trip lever 74 the gage slide 50 will not be moved downward, thereby insuring 55 against the gage 44 being forced with marking

pressure against the outsole of the shoe during the heel breeding operation.

Upon continued downward movement of the treadle rod 150 the clutch of the machine is tripped, the operating slide 78 (Fig. 1) being moved downward and moving with it the knife slide 68 to cause the heel of the shoe to be breasted. The knife slide 68 moves downward together with the operating slide 78 until the arm 72 of the bell-crank trip lever 74 engages the abutment 66, whereupon the lever is swung in a clockwise direction, as viewed in Fig. 3, from beneath the block 174 carried by the operating slide, with the result that downward movement of the knife slide, and therefore the knife 32, ceases. The operating slide 78 continues through its cycle and during its upward movement engages the leather facing 170 of the overhanging flange 166 secured to the upper portion of the knife slide 68 to raise said slide to its starting position shown in Fig. 3. During the upward movement of the knife slide 68 the bell-crank lever 74 moves back to its starting position beneath the block 174 (Fig. 3) and the gage slide 50 is moved to its raised inoperative position, shown in Fig. 4.

After the heel has been breasted, the treadle 152 is released, whereupon the lever 298 (Figs. 3 and 5) is again forced by the spring 305 against the cam pulley 280, and the presser plate 28 is moved to its raised position away from the heel 20 of the shoe 22.

The operator then swings the jack 26 to its loading position, causing the cable-operated pulley 314 to rotate clockwise, as viewed in Fig. 2, against the action of the cable tensioning spring 329. The pulley 314 has secured to it a rearwardly projecting stud 332 (Fig. 5), which, during the above-mentioned clockwise rotation of the pulley 314, engages a forward extension of the pin 312 carried by the cam 284, thereby causing said cam, together with the cam pulley 280, to be rotated clockwise, as viewed in Fig. 2, against the action of the coil spring 290. As the cam pulley 280 is thus rotated, its rearwardly extending lock pin 296 engages the under face 334 (Fig. 3) of the lever 298, causing said lever to be swung away from the cam pulley.

When the jack 26 is in its loading position the lock pin 296 has been rotated to a position in which it is slightly spaced from the lever 298, which, at that time, has moved behind the lock pin into engagement with the cam pulley 280.

After the shoe, the heel of which has been breasted, has been removed from the jack 26 and another shoe has been placed thereon, the jack is moved back to its vertical operative position. The operator, as above described, then moves the shoe to its proper lengthwise position in the machine as he first depresses the treadle 152, further downward movement of the treadle causing the cocked cam pulley 280 to be released. Upon further depression of the treadle 152 the clutch of the machine is tripped to breast the heel.

Having described my invention, what I claim as new and desire to secure by Letters Patent of the United States is:

1. In a heel breeding machine, means for supporting a shoe, a gage constructed and arranged to occupy a crease formed between an outsole of the shoe and the forward end of the attaching face of an unbrested heel attached to the shoe, a heel breeding knife, and means operatively associated with the gage for varying the cutting stroke of the knife in accordance with the position of said gage.

2. In a heel breeding machine, means for supporting a shoe, a heel breeding knife mounted for reciprocation, a work positioning gage having a tip constructed and arranged to be positioned approximately in the path of reciprocation of the knife, and means operatively associated with the gage for limiting the breeding movement of the knife when it arrives at the tip of said gage.

3. In a heel breeding machine, a support for a shoe having a heel, a breeding knife movable heightwise of the heel, a gage constructed and arranged to be positioned between an outsole of the shoe and the forward end of the attaching face of said heel, a clamp movable against the tread end of the heel and co-operating with the support to secure the shoe against movement, and means operatively connected to said gage for limiting the breeding movement of said knife in accordance with the position of said gage.

4. In a heel breeding machine, means for positioning a shoe having a heel, a breeding knife movable heightwise of said heel, a gage constructed and arranged to occupy a space between an outsole of the shoe and the forward end of the attaching face of said heel, and mechanism for limiting the breeding movement of the knife, said mechanism being operable at a predetermined portion of the breeding movement of said knife in accordance with the position of said gage.

5. In a heel breeding machine, means for positioning and clamping a shoe, a heel breeding knife, a swivelled gage for testing the position of the shoe, and means operatively connected to the gage for varying the breeding stroke of said knife in accordance with the setting of said gage.

6. In a heel breeding machine, a support for a shoe having an unbrested heel, a reciprocatory breeding knife, a reciprocatory abutment, a shoe positioned testing member which is mounted upon said abutment for pivotal movement about an axis, said member being unbalanced about said axis, a stop for limiting movement of said member about said axis in one direction, and means for causing the knife to move variable distances in accordance with the position of the abutment.

7. In a heel breeding machine, a support for a shoe having an unbrested heel, a reciprocatory breeding knife, a reciprocatory abutment, a shoe position testing member having a gaging tip which is movable heightwise of the shoe together with the abutment and is tiltable upon said abutment about an axis which is disposed at approximately right angles to the path of movement of the abutment and is arranged approximately in the path of reciprocation of said knife, said tip being arranged approximately in said axis irrespective of the angular position of the testing member on the abutment, and means operable at a particular portion of the breeding stroke of the knife in accordance with the position of said abutment for causing the breeding movement of the knife to cease when a cutting edge of the knife arrives at a position approximately in engagement with the tip of the gage.

8. In a heel breeding machine, a support for a shoe having an unbrested heel, a reciprocatory breeding knife, a movable abutment, a position testing member which is mounted upon the abutment for pivotal movement about an axis and which has an arm arranged outside said axis and terminating in a gaging tip lying approximately in said axis, said abutment being movable heightwise of the shoe to cause said arm to en-

gage the shank portion of the outsole of the shoe to tilt the arm as the shoe is positioned in order to facilitate the registration of a crease between the outsole and the forward end of the attaching face of the heel with said tip, and means for causing the knife to move variable distances during its breeding strokes in accordance with different positions of the abutment.

9. In a heel breeding machine, means for supporting a shoe, a knife mounted for reciprocation to breast a heel of the shoe, an abutment, a sickle-shaped gage having a shank portion which is pivotally mounted upon the abutment and a tip which is constructed and arranged to occupy a crease formed between an outsole of the shoe and the forward end of the attaching face of the unbrested heel and is in approximate alinement with the pivotal axis of said shank portion, means for limiting pivotal movement of the gage about said axis, and means movable in response to movement of the knife and constructed and arranged to engage said abutment for limiting breeding movement of the knife in accordance with the position of said gage.

10. In a heel breeding machine, means for positioning and clamping a shoe having a heel, a heel breeding knife movable heightwise of said heel, a movable abutment, a gage for testing the position of the rear end of the shank portion of an outsole of the shoe, said gage being pivotally connected to the abutment, and knife operating mechanism, said abutment being constructed and arranged to be engaged by portions of said knife operating mechanism to limit the breeding movement of the knife in accordance with the position of said abutment, said gage being so constructed and arranged that its work testing portion remains in approximately the same location relative to the abutment in different angular positions of the gage on said abutment.

11. In a heel breeding machine, means for supporting a shoe having an unbrested heel, a reciprocating knife for breeding said heel, a movable abutment the position of which regulates the extent of reciprocation of the knife, and a sickle-shaped gage having a cylindrical shank movable together with the abutment and pivotally movable about the axis of its shank with relation to the abutment, said gage having a tip which is in approximate alinement with the axis of the shank and is constructed and arranged to occupy a crease between the shank of the outsole of the shoe and the forward end of the attaching face of the unbrested heel attached to the shoe, said gage having its center of gravity offset from said axis to cause the gage to swing about said axis to an inoperative position with relation to the abutment when not in engagement with the work, said gage being swung about said axis under pressure of the work to cause the gage to tilt in accordance with the shank angle of the outsole of the shoe, thereby facilitating the registration of said crease with the tip of the gage.

12. In a heel breeding machine, a support for a shoe which is mounted upon a last and to which an unbrested heel is attached, said support being tiltable laterally in order to tilt the shoe laterally, a pair of yieldable members constructed and arranged to be engaged by the forward upper side portions of the heel to facilitate tilting the shoe laterally to a desired position, and a presser plate co-operating with the support to clamp the shoe in the machine.

13. In a heel breeding machine, a support for

a shoe having an unbrested heel, a gage constructed and arranged to engage the extreme rear end of the shank portion of an outsole of the shoe, a clamp constructed and arranged to engage the tread end of the heel and to co-operate with the support in positioning the shoe and holding it against movement, a knife, means, comprising trip-off mechanism, for operating said knife to breast said heel, an abutment movable in response to movement of said gage, said abutment being constructed and arranged to operate said trip-off mechanism for limiting the breeding movement of the knife in accordance with the position of said abutment, and means for positively holding said abutment against movement as said trip-off mechanism is forced against the same, thereby insuring against the gage marring the outsole of the shoe.

14. In a heel breeding machine, means for supporting against movement a shoe having a built-up heel, a knife for removing material from the breast of the heel, a testing member constructed and arranged to occupy a crease formed between the forward end of the attaching face of the heel and the shank of an outsole of the shoe, an abutment operatively connected to said testing member, means responsive to movement of the knife and constructed and arranged to engage said abutment for limiting the breeding stroke of the knife when said knife has moved into engagement with the outsole of the shoe, and means for holding the abutment against movement under pressure of the second-named means to insure against the testing member marking the outsole.

15. In a heel breeding machine, means for securing in position a shoe which is mounted upon a last and has a built-up heel, a movable knife for removing material from the breast of said heel, a gage constructed and arranged to occupy a crease formed between the forward end of the attaching face of the heel and an outsole of the shoe, a slide upon which said gage is pivotally mounted, said gage having a work-engaging portion in alinement with its axis of pivotal movement upon the slide, an abutment mounted upon said slide, means responsive to movement of the knife for engaging said abutment to limit breeding movement of the knife in accordance with the position of the gage, and a member movable into engagement with the slide to insure against displacement of said slide when said abutment is engaged by the last-named means.

16. In a heel breeding machine, means for supporting and clamping a shoe having a built-up heel, a knife movable toward the support to remove material from the breast of the heel, a testing member constructed and arranged to occupy a crease formed between the forward end of the attaching face of the heel and an outsole of the shoe, said member being mounted for pivotal movement about an axis which extends substantially along its work-engaging face, and means for moving the testing member together with and relatively to the knife.

17. In a heel breeding machine, means for supporting and clamping a shoe, a breeding knife movable heightwise of a built-up heel of the shoe to remove material from the breast of said heel, power operated means for moving said knife, mechanism for actuating said knife operating means, a gage movable into engagement with an outsole of the shoe for testing the position of said outsole, means operatively connected to said gage for limiting the breeding movement

of the knife in accordance with the setting of said gage, mechanically operated means for moving the gage a substantial distance away from the outsole of the shoe after the heel has been breasted, preparatory to removing the shoe from the machine, and means independent of said actuating mechanism for releasing the gage to permit it to move by gravity into engagement with the outsole of the shoe prior to the operation of the knife.

18. In a heel breasting machine, a movable support for a shoe, means co-operating with the support to clamp the shoe in the machine, a knife movable heightwise of a built-up heel attached to the shoe to remove material from the breast of said heel, a gage for testing the position of the outsole of the shoe, mechanically operated means for moving the gage a substantial distance away from the outsole of the shoe after the heel has been breasted, preparatory to removing the shoe from the machine, and mechanism responsive to movement of the shoe support for releasing the mechanically operated means when the support has been moved to a predetermined position, said gage when released being free to move into engagement with the outsole of the shoe.

19. In a heel breasting machine, a support for a shoe having a built-up heel, a clamp co-operating with the support to secure the shoe in position, a movable gage for testing the position of the shoe, an abutment movable into different operative positions in accordance with the position of the gage, a knife movable to breast the heel of the shoe, a connection through which the knife is operated, said connection being movable into engagement with said abutment for causing the breasting movement of said knife to cease in accordance with the position of the abutment, a member for backing up the abutment against pressure exerted by said connection, means for mechanically moving the gage a substantial distance away from an outsole of the shoe, preparatory to removing the shoe from the machine, and means responsive to movement of the support for disconnecting the gage from said means in order to permit said gage to move by gravity into engagement with the outsole of the next shoe to be operated upon in the machine.

20. In a heel breasting machine, a support for a shoe having an unbreasted heel, a presser member co-operable with the support to hold the shoe in position to be operated upon, a heel breasting knife movable toward an outsole of the shoe to trim material from the breast of the heel, means for operating the knife, mechanism for limiting the movement of the knife when it engages said outsole to insure against said knife penetrating the outsole, said mechanism comprising a position testing gage constructed and arranged to engage the rear end of the shank portion of the outsole of the shoe, and means for moving said gage to an inoperative position away from the shoe, preparatory to removing the shoe from the machine, said gage being movable, independently of movement of the knife, by gravity to its operative position in engagement with the outsole of the shoe.

21. In a heel breasting machine, a support for a shoe, a member associated with the support to secure the shoe in a position to be operated upon, a breasting knife movable toward and away from said support, a gage for testing the position of the shoe, means movable in response to movement of said gage for limiting movement of the knife toward the support, means for moving the

gage from its testing position to an inoperative position a substantial distance away from the support, said support being movable to and from a loading position, and means responsive to movement of the support for causing the gage to move into engagement with the shoe.

22. In a heel breasting machine, means for positioning a shoe having an unbreasted built-up heel, a breasting knife movable heightwise of the heel, a gage for testing the position of the rear end of the shank portion of an outsole of the shoe, means associated with the gage for limiting movement of the knife toward the outsole of the shoe in accordance with the position of said gage, means for moving the gage to an inoperative position away from the shoe, the heel of which has been breasted, in response to retractive movement of the knife, and means independent of movement of the knife for causing the gage to move relatively to the knife to an operative position against the shank portion of the outsole of the shoe next to be operated upon.

23. In a heel breasting machine, a support for a shoe having a built-up heel, a breasting knife movable heightwise of the heel, means movable into an operative position in engagement with an outsole of the shoe for limiting breasting movement of the knife, mechanism responsive to movement of the knife for moving said means to an inoperative position away from the support, and mechanism responsive to movement of the support for enabling said means to move into its operative position.

24. In a heel breasting machine, a support for a shoe, means for clamping the shoe against movement upon the support, a gage movable into engagement with an outsole of the shoe, a knife movable heightwise of a built-up heel attached to the shoe to breast said heel, means comprising a stop operatively connected to the gage for limiting breasting movement of the knife upon its engagement with said outsole, means responsive to movement of the knife away from the outsole for moving said gage to an inoperative position away from the shoe support and for temporarily retaining it in said position, said support being movable to and from a loading position, and means responsive to movement of the support from its loading position to its operative position for permitting the gage to be moved into engagement with the outsole of the shoe.

25. In a heel breasting machine, means for securing a shoe in position, said means comprising a jack movable from an operative position, in which a built-up heel of the shoe is breasted, to a loading position in which the shoe is removed from the jack preparatory to operating upon another shoe, a knife mounted for movement to breast the heel of the shoe, a slide to which the knife is secured and which carries a trip-off drive member, a gage for testing the position of the shoe, an abutment for carrying said gage, said abutment being constructed and arranged to be engaged by the trip-off drive member during the breasting movement of the knife to limit said movement, means responsive to movement of the jack for backing up said abutment in order to insure against movement of the abutment when it is engaged by the trip-off drive member, and means for securing the abutment to the knife slide to cause the gage to move to an inoperative position a substantial distance away from an outsole of the shoe preparatory to moving the jack to its loading position.

26. In a heel breasting machine, means for se-

curing a shoe in position, said means comprising a jack movable from an operative position in which a built-up heel of the shoe is breasted to a loading position in which the shoe is removed from the jack preparatory to operating upon another shoe, a knife mounted for movement to breast the heel of the shoe, a slide to which the knife is secured and which carries a trip-off drive member, a gage for testing the position of the shoe, an abutment carrying said gage, said abutment being constructed and arranged to be engaged by the trip-off drive member during the breasting movement of the knife to limit said movement, means responsive to movement of the jack for backing up said abutment in order to insure against movement of the abutment when engaged by the trip-off member, means for securing the abutment to the knife slide to cause the gage to move to an inoperative position a substantial distance away from an outsole of the shoe preparatory to moving the jack to its loading position, and means responsive to movement of the jack during its movement away from its loading position for disconnecting the abutment from the knife slide, thereby enabling the gage to move into engagement with the shoe.

27. In a heel breasting machine, means for securing a shoe in position, said means comprising a jack movable from an operative position in which a built-up heel of the shoe is breasted to a loading position in which the shoe is removed from the jack preparatory to operating upon another shoe, a knife mounted for movement to

breast the heel of the shoe, a slide to which the knife is secured and which carries a trip-off drive member, a gage for testing the position of the shoe, an abutment carrying said gage, said abutment being constructed and arranged to be engaged by the trip-off drive member during the breasting movement of the knife to limit said movement, a cam, a spring for operating said cam, a follower responsive to movement of said cam, and means responsive to movement of the jack for causing the release of the cam, thereby enabling the cam operated by the spring to force the follower against said abutment to back up the abutment against movement when it is engaged by the trip-off drive member.

28. In a heel breasting machine, means for securing a shoe in position, a reciprocatory knife slide and a reciprocatory operating slide, a gage for testing the position of the shoe, an abutment operatively connected to said gage, a block secured to the operating slide and having a flat face, and a bell-crank lever pivoted to the knife slide and normally having a flat face of one of its arms in engagement with the flat face of said block to cause the knife slide to reciprocate with the operating slide, said bell-crank lever having another arm which during the reciprocation of the knife slide engages said abutment, causing said flat face of the bell-crank lever to move away from the flat face of the block to cause reciprocatory movement of the knife slide, and, therefore, movement of the knife, to cease.

ERASTUS E. WINKLEY.
